DESIGN FOR A COOKING VESSEL OR SIMILAR ARTICLE

Carlton G. Towne, Pittsburgh, and Elsie H. Wunderley, New Kensington, Pa., assignors to The Aluminum Cooking Utensil Company, New Kensington, Pa., a corporation of Pennsylvania

Application November 12, 1935, Serial No. 59,510

Term of patent 7 years

To all whom it may concern:

Be it known that we, Carlton G. Towne and Elsie H. Wunderley, citizens of the United States, residing, respectively, at Pittsburgh, in the county of Allegheny and State of Pennsylvania, and at New Kensington, in the county of Westmoreland and State of Pennsylvania, have invented a new, original, and ornamental Design for a Cooking Vessel or Similar Article, of which the following is a specification, reference being had to the accompanying drawing, forming a part thereof.

Fig. 1 is a top plan view of a cooking vessel or similar article embodying our new design.

Fig. 2 is a side view of a cooking vessel or similar article, part being broken away to show the top in cross-section.

We claim:

The ornamental design for a cooking vessel or similar article as shown and described.
